UNITED STATES PATENT OFFICE.

JOSEPH W. SKERSICK AND JOSEPH F. SKERSICK, OF BERTRAM, IOWA.

WRENCH.

SPECIFICATION forming part of Letters Patent No. 623,188, dated April 18, 1899.

Application filed February 13, 1899. Serial No. 705,462. (No model.)

To all whom it may concern:

Be it known that we, JOSEPH W. SKERSICK and JOSEPH F. SKERSICK, citizens of the United States, residing at Bertram, in the 5 county of Linn and State of Iowa, have invented certain new and useful Improvements in Wrenches; and we do hereby declare the following to be a full, clear, and exact description of the invention, such as will enable others 10 skilled in the art to which it appertains to make and use the same.

The object of this invention is to so improve the construction of a monkey-wrench as to admit of its jaws being clamped tightly on a nut, 15 bolt, or other object, so as to hold the same as in a vise.

The nature of the invention is fully disclosed in the description and claims following, reference being had to the accompanying 20 drawings, in which—

Figure 1 is a side view of our improved wrench. Fig. 2 is a central longitudinal section of the same in the same plane as Fig. 1.

Similar letters of reference indicate corresponding parts.

In the drawings, A designates the outer jaw of the wrench and has a rectangular shank A' and a terminal screw-threaded portion A² to take a knurled thumb-nut B. The shank of 30 this jaw fits in a rectangular socket C' in the handle C, which is preferably of metal, and has an opening at C² to receive the thumb-nut and adjacent abutments C', the handle being for the most part hollow, as shown in Fig. 2.

Suitable holes in these abutments admit the 35 threaded portion of the shank and allow for the adjustment of the jaw to any desired extent.

The inner jaw D is provided also with a 40 rectangular hole to receive the shank of the outer jaw. It is further provided with a tail-piece D', which enters a recess C⁴ at the back side of the handle and serves to brace the inner jaw against diagonal strain when pressure 45 is brought to bear on the jaw proper.

On the front portion of the handle, adjacent to the inner jaw, is a projection or lug C⁵, and to this is pivoted a bifurcated lever E, the legs E' of which straddle the shank of 50 the outer jaw and lie between the jaw end of the handle and the adjacent face of the inner jaw. This lever also connects by a link F

with the inner jaw, a suitable socket D² being formed therein to receive said link. The other end of the lever, when closed down to 55 locking position, as shown in full outlines in both figures, lies close to the back of the wrench-handle and may be conveniently grasped by the operator as a part of the handle.

The action of the wrench is illustrated in Fig. 1. For ordinary use the wrench is left in the position shown in full. When, however, it is desired to grip anything tightly, the lever is thrown up, as shown by the dotted 65 lines, which draws the inner jaw back a little toward the handle. The wrench is then adjusted to the object in the usual way by the use of the thumb-nut, and finally the lever is pressed down to its locking position against 70 the handle, which causes the jaws to grip the object very tightly.

It is to be noted that the lever has but a limited movement, being stopped in one direction by the inner jaw and in the other direction by the handle. This prevents its getting out of easy reach of the operator. It will be observed also that the pressure of the toggle-lever is practically in line with the resistance and there is consequently but little 75 80 diagonal strain on the inner jaw to throw it out of parallel with the outer one and cause it to bind on the shank thereof. The tail-piece, furthermore, tends to relieve the jaw of whatever side strain there may be, as already specified.

The jaws may be smooth, as in Fig. 1, for ordinary use, or serrated, as in Fig. 2, and thus serve for gripping pipe and the like.

Having thus described our invention, what 90 we claim as new, and desire to secure by Letters Patent, is—

1. In a wrench, the combination of an outer jaw having a rectangular shank and screw-threaded portion, a handle adapted to receive 95 the same, with a suitable adjusting-nut, an inner jaw adapted to slide on the shank of the outer jaw, a bifurcated lever straddling the shank between the inner jaw and the handle, and pivoted to a projection of said handle, 100 and a link connecting said lever with said inner jaw, substantially as and for the purpose set forth.

2. In a wrench, the combination of an outer

jaw having a rectangular shank and screw-threaded portion, a handle to receive the same, having a nut-socket and an adjusting-nut therein, an inner jaw fitted to slide on the shank of the outer jaw, and having a tailpiece on the back side entering a socket therefor in the handle, and a bifurcated lever straddling the shank, and pivotally connected near the ends of its legs with a projecting portion of the handle, and a link connecting said legs

also with the inner jaw, substantially as and for the purpose set forth.

In testimony whereof we affix our signatures in presence of two witnesses.

JOSEPH W. SKERSICK.
JOSEPH F. SKERSICK.

Witnesses:

CHARLIE SKERSICK,
J. M. ST. JOHN.
